CONVERTIBLE CHAIR LOUNGE

Alexander J. Duke, Los Angeles, Calif.

Application June 21, 1952, Serial No. 20,300

Term of patent 14 years

(Cl. D15—11)

To all whom it may concern:

Be it known that I, Alexander J. Duke, a citizen of the United States of America, residing in the city of Los Angeles, county of Los Angeles, State of California, have invented a new, original, and ornamental Design for a Convertible Chair Lounge, of which the following is a specification, reference being had to the accompanying drawing forming a part thereof.

Fig. 1 is a perspective view of a convertible chair lounge in folded position and with the cushion therein, showing my new design;

Fig. 2 is a perspective view of the opposite side of the chair lounge in extended position and with the cushion therein;

Fig. 3 is a rear elevational view; and
Fig. 4 is a bottom view of the chair lounge in extended position.

I claim:

The ornamental design for a convertible chair lounge, substantially as shown.

ALEXANDER J. DUKE.
